DRIVING MECHANISM FOR WASHING MACHINES.

1,416,479.

Specification of Letters Patent. Patented May 16, 1922.

Application filed October 20, 1920. Serial No. 418,240.

To all whom it may concern:

Be it known that I, JOSEPH F. LAMB, a citizen of the United States, residing at city of New Britain, county of Hartford, State of Connecticut, have invented certain new and useful Improvements in Driving Mechanism for Washing Machines, of which the following is a full, clear, and exact description.

10 My invention relates to driving mechanisms that are particularly adapted for washing machines and has for its object to produce a new and improved compact means for securing a small number of complete revolutions of a reversing washing machine cylinder between reversals; to reduce the size and number of the gears for securing a given reduction of the shaft carrying the reversing cams; to provide means for the 15 quick opening of the reversing clutch so as to avoid the stripping of the surfaces of its clutch teeth; to make the high speed gearing of a washing machine a self-contained and separable structure; to provide a gear 20 housing for the high speed gearing adapted to contain liquid lubricant sufficient to partially submerge the shafting of said gearing; to reduce the frequency of necessary lubrication of the high speed shafts; to reduce 25 the noise of the reversing mechanism; to confine the high speed shafts of the machine to the lower part thereof and to lower the center of gravity of the machine as a whole by the location of the high speed gearing 30 and its motor; to support the high speed gearing from below and provide a suitable drip-pan therefor.

The following is a description of an embodiment of my invention, reference being 40 had to the accompanying drawings, in which,

Fig. 1 shows an end elevation of a washing machine embodying my invention;

Fig. 2 shows a side elevation of the same;

45 Fig. 3 is a plan view of the reduction gearing of the washing machine and the casing therefor;

Fig. 4 is a side elevation of the casing with the cover therefor, certain parts of 50 the gearing being shown in dotted lines;

Fig. 5 is a detail view of a Geneva movement used in embodying part of my invention;

Fig. 6 is a sectional view on the line 6—6, 55 Fig. 3; and,

Fig. 7 is a sectional view on the line 7—7, Fig. 3.

Referring more particularly to the drawings, 1 is a framework having rectangular sides and top and supporting side and cross bars 2, 2'. 3 is the usual tub having within it a reversing washing cylinder 4. 5 is a vertical shaft geared to the washing cylinder for actuating the same. 6 is a vertical shaft for operating the wringer mechanism 7. Below the tub is an electric motor 8 mounted upon a wooden base 9, which is supported by certain of the bars 2, 2'. 10 is a gear casing supported by bars 2, 2' and secured thereto by screws 11. This casing is provided with a cover made in two parts 12, 12' secured thereto. This casing and cover constitute a housing completely enclosing the greater part of the gearing of the washing machine. This gearing consists of a small pinion 13 mounted upon a shaft driven by the motor 8, this shaft being mounted in a bushing 14 held in place by a set-screw 15 and having its end protruding through the side of the casing so as to enter a coupling 16. The interior of the casing is divided by a partition 17, which is integral with the sides and bottom of the casing, which casing constitutes a single casting having external sides 18 and 19 which form supports 80 for the shaft journals. The pinion 13 meshes with a large gear 20, which is rigidly mounted upon a shaft 21 on which is also rigidly mounted a small pinion 22. The ends of this shaft 21 are carried by bushings 23, 23' which are supported in the walls 17 and 19 respectively and secured therein by set-screws. The pinion 22 meshes with a gear 24 rigidly mounted on a shaft 25. This shaft is journaled in bushings 26, 26' carried by the walls 17 and 18 respectively. Upon the opposite sides of the wall 17 from the gear 24 is the driving member 27 of a Geneva movement, and loosely mounted upon the shaft 25 are beveled gears 28, 28' having clutch teeth 29, 29' with which similar clutch faces upon a sliding clutch member 30 alternately engage. This sliding clutch member 30 is splined to the shaft 25 so as to rotate therewith. The clutch member 30 is actuated by a lever 31, whose lower end is pivoted at 32 to a bearing secured to the base of the casing. This lever is provided with an anti-friction projection 33 which is engaged alternately by 90 95 100 105 110

two cams 34, 34' upon a shaft 35 so as to be moved thereby in one direction or the other beyond its dead center. The cams 34, 34' are double-faced so that the lever 31 is shifted in the manner described irrespective of the direction of revolution of the shaft 35. On the shaft 35 is mounted a second member 36 of the Geneva movement, which member is actuated by the roller 37 of the driving member 27 of the Geneva movement. This shaft 35 has one end carried by a bushing 38 secured in the wall 18 of the casing and is, at a point between the cam 34' and the driven member 36 of the Geneva movement, supported by a journal supported in an upwardly extending projection 39, which is integral with the bottom of the casing.

The upper end of the lever 31 is provided with a bearing block 40 pivoted thereto, in which moves a pin 41 whose upper spherical end is movably held against an abutment 42 secured by bolts 43 to the upper end of the projection 39. This pin 41 is surrounded by a compression spring 44, which, after the lever 31 has been thrown beyond its dead center, compels the lever to complete its throw so as to cause the clutch member 30 to make engagement with one or the other of the gears 28, 28' according to its direction of throw. The gears 28 and 28' are in constant mesh with a double-faced beveled gear 45, which is rigidly connected to a rotatable shaft 46 journaled in a bushing 47 carried by one of the end walls of the casing and secured thereto by a set-screw 48, as shown in Fig. 7. Meshing with the outer face of the double-faced gear 45 is a beveled gear 49 rigidly connected to the vertical shaft 50, which is journaled in a bushing 51 supported by the cover 12. The lower end of this shaft 50 is removably held within a bearing in the casing 10 directly above the bushing 47. The shaft 50 is surrounded by a ring 52 secured thereto by a set-screw 53 so that when the cover 12 is removed the shaft 50, together with the beveled gear 49, is removed therewith.

The top of the casing extends well above the horizontal shafts hereinbefore referred to and the bushings therefor, and the casing is adapted to contain liquid lubricant in sufficient quantity to substantially submerge said horizontal shafts and also said clutch member 30.

In order to permit the assembling of the parts, the outer walls of the casing are provided with openings in alignment with one end of each horizontal shaft, which openings are closed by liquid-tight closures 54, preferably in the form of sheet steel plugs, as shown in section in Fig. 3.

The bearing for the shaft of the pinion 13 is provided with a packing gland 55 which is held compressed in the bushing 14 by the flange 56 and the ring 57 secured to said

shaft by a set-screw, as shown in Fig. 3. The casing is thus made liquid tight so that there is practically no danger of leakage even if the oil therein is sufficient to reach to near the top of the casing. The result is that the gears and pinions above described may be submerged in oil up to their points of engagement, insuring adequate lubrication which lasts for a long time and which also practically eliminates the noise due to the operation of the gearing.

The clutch faces of the gears 28 and 28' and the clutch member 30 may also be kept immersed in oil, with the result that the noise due to the shifting of the clutch member 30 and its engagement with one or the other of the clutch faces 29 and 29' is greatly reduced and practically eliminated.

The use of the Geneva movement composed of the parts 27 and 36 results in a very great reduction taking place between the shaft 25 and the shaft 35, the reduction in the present instance being twelve to one. It further results in a relatively high speed for the shaft 35 when it is in motion, with the result that the cams 34, 34' are given a quick movement when acting and thus withdraw the clutch member 30 from the teeth 29, 29' with a quick movement, greatly reducing the danger of stripping the faces of those teeth during the period when disengagement is taking place. Furthermore, the cams 34 and 34' are so timed that a complete throw of the lever 31 takes place during a single one of the intermittent movements of the cams 34, 34', so that not only is the clutch 30 shifted quickly, but whenever its movement is started it is immediately completed.

The vertical shaft 50 is coupled to the shaft 5, which, as shown in Fig. 1, operates the cylinder 4 within the tub. In order to operate the shaft 6 of the wringer, I provide the casing with a vertical shaft 58, whose lower end is journaled in a bushing 59, which is inserted through an opening in the bottom of the casing shown by a closure 60 similar to the closures 54. This shaft 58 carries a beveled gear 61, which is driven by a beveled gear 62, mounted on a shaft 63, which carries a pinion 64 engaging with the gear 24. This shaft 63 is journaled in a bushing 65 which is carried by an upward projection 66 integral with the bottom and one side of the casing and is secured therein by a set-screw 67. The movement therefore is transmitted from the pinion 13 to the shaft 58 through a direct train of gearing, this movement being more rapid than a movement of the shaft 25 but very materially reduced from that of the shaft of the pinion 13. The shaft 63 is inserted through an opening in the side wall of the casing closed by a closure 68, similar to the closure 54.

The cover members 12, 12' are provided

with screw plugs 69, 69' located above the two compartments of the casing through which oil can be introduced. The cover is provided with two upwardly extending holes 5 low portions 70 and 71, housing the abutment 42 and the upper portion of the gear 20 respectively, and is provided with downwardly extending flanges 72, 72' with the result that the cover will contain and hold 10 considerable oil when inverted, as sometimes happens when machines are being transported. Inasmuch as, however, at such times the shafts 50 and 58 are not in rotation, there is little danger of oil leaking out at 15 the points where those shafts enter.

It is to be noted that the horizontal shafts of the machine from the shaft of the pinion 13 to and including the shafts 25 and 63 are all parallel and in substantially the same 20 horizontal plane, and that the vertical shafts are in a plane which is substantially parallel to parallel planes passing through the axes of those horizontal shafts. It is further to be noted that a vertical projection of the 25 framework of the machine falls outside all of the gearing and the motor for driving the same, and that the location of the casing with its gearing and the motor for driving the same at the bottom of the frame brings 30 the center of gravity well toward the bottom and well toward the medial vertical axis of the machine. The result of this is that the machine is very steady and the danger of its tipping when the wringer 7 is 35 swung outward is eliminated. The rotation of the motor almost directly under the central axis of the tub and on the other side of the frame from the wringer support contributes very largely to this result.

40 With the apparatus shown the number of revolutions between reversals of the washing cylinder is, by the use of a compact and self-contained gearing, reduced to two revolutions. This results in preventing the "balling" of the clothes, which occurs when there 45 is a large number of revolutions between reversals. Furthermore, all the gearing which is of high speed and requires frequent lubrication is located in the self-contained casing, 50 so that little lubricant has to be applied to any bearings in the walls of the tub adjacent to the axes of the washing cylinder, thus eliminating the danger of having lubricant leak into the tub as is the case where a large 55 supply of lubricant is necessary adjacent to the axis of the cylinder. Furthermore, in the arrangement above described, the high speed shafts where wearing is likely to occur are all removed from adjacent to the tub 60 walls so that the necessary wearing of the high speed shafts and their journals can not result in increasing the danger of leakage of oil into the tub.

In order to prevent the dripping of any 65 oil upon the floor, which may leak on ac-

count of the dislodgment of one of the closures, such as 54, or from spilling of oil when introducing it through the openings controlled by the plugs 69, 69', I provide a drip-pan 73, which extends completely beneath the casing 10 and lies between the legs 70 of the casing and the bars 2, 2'.

It is also to be noted that the member 36 of the Geneva movement of the gears 13, 20 and 22 lie on the same side of the shaft 25 75 and together with the shaft 25 form some sort of a U-shaped arrangement, while, considering the gearing as a whole, the arrangement is H-shaped, the shaft 25 constituting the crossbar of the H, both of which arrangements contribute to the compactness of 80 the gearing.

As will be evident to those skilled in the art, my invention permits of various modifications without departing from the spirit 85 thereof or the scope of the appended claims.

What I claim is:

1. In a washing machine, the combination of a power-driven shaft, a countershaft driven thereby, a Geneva movement driven 90 by said countershaft, reversing mechanism comprising a shiftable clutch member, and cams intermittently driven by said Geneva movement for shifting said clutch member.

2. In a washing machine, the combination of a power-driven shaft, a countershaft driven thereby, a Geneva movement driven by said countershaft, reversing mechanism comprising a shiftable clutch member, and cams intermittently driven by said Geneva 95 movement for shifting said clutch member, said cams being so timed that any throw of said member by said cams is completed during a single movement of the intermittently moving member of said Geneva movement. 100

3. A shaft having two beveled gears loosely mounted thereon and provided with opposing clutch faces, a clutch member mounted on said shaft between the clutch faces on said beveled gears, a third gear engaging both of said beveled gears, a lever for shifting said clutch member, a shaft parallel to said first mentioned shaft, two cams on said second shaft for actuating said lever, and a Geneva movement, the driving member of which is fast on said first shaft and the driven member of which is fast on 105 said second shaft. 110

4. A shaft having two beveled gears loosely mounted thereon and provided with opposing clutch faces, a clutch member mounted on said shaft between the clutch faces on said beveled gears, a third gear engaging both of said beveled gears and adapted to drive a washing cylinder, a lever for shifting said clutch member, a shaft parallel to said first mentioned shaft, two cams on said second shaft for shifting said lever alternately in opposite directions, a Geneva movement, the driving member of 115 120 125 130

65

which is on said first shaft and the driven member on said second shaft, a large gear on said first shaft, a third shaft, and a small gear on said third shaft meshing with said 5 large gear and driving the same.

5. A shaft having two beveled gears loosely mounted thereon and provided with opposing clutch faces, a clutch member mounted on said shaft between the clutch 10 faces on said beveled gears, a third gear engaging both of said beveled gears and adapted to drive a washing cylinder, a lever for shifting said clutch member, a shaft parallel to said first mentioned shaft, two cams 15 on said second shaft, a Geneva movement, the driving member of which is on said first shaft and the driven member on said second shaft, a large gear on said first shaft, a third shaft, a small gear on said third shaft meshing 20 with said large gear and driving the same, a fourth shaft, a small gear on said fourth shaft driven by said large gear, a vertical shaft and engaging beveled gears on said fourth and vertical shafts, said vertical 25 shaft being adapted to drive a wringer.

6. A horizontal shaft having two beveled gears loosely mounted thereon and provided with opposing clutch faces, a clutch member mounted on said shaft between the clutch 30 faces on said beveled gears, a third gear engaging both of said beveled gears and adapted to drive a washing cylinder, a lever for shifting said clutch member, a horizontal shaft parallel to said first mentioned shaft, 35 two cams on said second shaft, a Geneva movement, the driving member of which is on said first shaft and the driven member on said second shaft, a large gear on said first shaft, a third horizontal shaft, a small gear on said 40 third shaft meshing with said large gear and driving the same, a fourth horizontal shaft, a small gear on said fourth shaft driven by said large gear, a vertical shaft and engaging beveled gears on said 45 fourth and vertical shafts, and means for driving said large gear, said fourth shaft being adapted to drive a wringer, all of said shafts being in planes parallel to one another.

50. 7. A shaft having two beveled gears loosely mounted thereon and provided with opposing clutch faces, a clutch member mounted on said shaft between the clutch faces on said beveled gears, a third gear engaging both of said beveled gears and adapted to drive a washing cylinder, a shaft parallel to said first mentioned shaft, two cams on said second shaft for actuating said clutch member, a Geneva movement, the 55 driving member of which is on said first shaft and the driven member on said second shaft and imparts a quick motion to said cams and clutch member, and a liquid-tight casing carrying bearings for said shafts and gearing, the top of said casing rising above 60

said shafts and adapted to contain sufficient oil to submerge said clutch member.

8. The combination of a casing, a shaft mounted therein, two beveled gears loosely mounted thereon and provided with clutch 70 surfaces, a gear in constant mesh with said beveled gears, a clutch carried by said shaft, a clutch lever for actuating said clutch member, a spring for completing the throw of said clutch lever, cam surfaces acting to 75 move said clutch lever alternately in opposite directions beyond its dead center, cam actuating means consisting of a Geneva movement, the driving member of which is mounted on said shaft and the driven member 80 of which is rigidly connected to said cam, and a vertical shaft geared to the gear engaging said two beveled gears, said casing being adapted to contain sufficient oil to substantially submerge said clutch member. 85

9. The combination of a casing, a horizontal shaft mounted therein, a motor for driving said shaft, reducing gearing between said motor and said shaft, reversing mechanism actuated by said shaft, said 90 shaft and the axes of said reducing gearing and motor being parallel to one another and two vertical shafts mounted in said casing and in substantially a vertical plane parallel to said horizontal shaft, gearing connecting 95 one of said vertical shafts to said reversing mechanism, and gearing connecting the other vertical shaft to the reducing gear on said first mentioned shaft.

10. The combination of a casing a shaft 100 journaled therein, beveled gears loosely mounted thereon and provided with clutch surfaces, a clutch member mounted between said gears, a third gear engaging said gears, a second shaft parallel to said first shaft, 105 shifting cams mounted on said second shaft, a clutch lever actuated alternately in opposite relations by said cams, a gear upon said first shaft, a shaft approximately in alignment with said second shaft and carrying 110 reducing gearing engaging the gear upon said first shaft, a shaft for driving said reducing gearing, a fourth shaft having a gear thereon engaging the driving gear on said first shaft, and two upright shafts one 115 shaft geared to said last mentioned shaft and the other shaft geared to the gear engaging said two beveled gears respectively, and a cover for said casing through which said two vertical shafts pass. 120

11. The combination of a casing, a horizontal shaft mounted therein, two beveled gears loosely mounted thereon and provided with clutch surfaces, a gear in constant mesh with said beveled gears, a clutch member carried by said shaft, a spring for completing the throw of said clutch member, a horizontal shaft carrying cams acting to move said clutch member alternately in opposite directions beyond its dead center, 125 130

cam actuating means consisting of a Geneva movement, the driving member of which is mounted on said shaft and the driven member of which is rigidly connected to said 5 cam shaft, a vertical shaft geared to the gear engaging said two beveled gears, another gear mounted on said shaft, a motor for driving said shaft through said other gear, and reducing gearing between said motor 10 and said other gear, said casing having two compartments, one of which contains said other gear and reducing gearing, the other compartment containing the balance of said gearing and said cams and Geneva movement, 15 said compartments being adapted to contain sufficient oil to submerge said horizontal shafts.

12. The combination of a shaft, two beveled gears provided with opposing clutch 20 surfaces and loosely mounted thereon, a third gear in constant mesh with said two beveled gears, a clutch member on said shaft between said two beveled gears, a second shaft parallel to said first shaft, cams on 25 said second shaft for throwing said clutch member first in one direction and then in the other, means mounted on said two shafts for imparting to said second shaft an intermittent rotary movement, and means for 30 rotating said first shaft continuously, said cams being so timed as to effect the throwing of said clutch member out of engagement with the clutch surface of one of the gears during a single movement of said cam 35 shaft.

13. The combination of a shaft, two beveled gears provided with opposing clutch

surfaces and loosely mounted thereon, a third gear in constant mesh with said two beveled gears, a clutch member on said shaft 40 between said two beveled gears, a second shaft parallel to said first shaft, cams on said second shaft for throwing said clutch member first in one direction and then in the other, means mounted on said two shafts for imparting to said second shaft an intermittent rotary movement, 45 means for rotating said first shaft continuously, said casing being adapted to contain oil sufficient to submerge said shafts, and a cover for said casing having cavities adapted to receive and contain oil when said casing and cover is inverted.

14. The combination of a shaft, two beveled gears provided with opposing clutch 55 surfaces and loosely mounted thereon, a third gear in constant mesh with said two beveled gears, a clutch member on said shaft between said two beveled gears, a second shaft parallel to said first shaft, cams on 60 said second shaft for throwing said clutch member first in one direction and then in the other, means mounted on said two shafts for imparting to said second shaft an intermittent rotary movement, means for rotating 65 said first shaft continuously, said casing being adapted to contain oil sufficient to submerge said shafts, a cover for said casing having cavities adapted when inverted to receive and contain oil, a vertical shaft 70 geared to the gear engaging said two beveled gears and carried by said cover so as to be removable therewith.

JOSEPH F. LAMB.
